UNITED STATES PATENT OFFICE.

MELVIN B. BENSON, OF SUPERIOR, WISCONSIN.

TELEMOTOR.

1,374,179.

Specification of Letters Patent. Patented Apr. 12, 1921.

Application filed December 27, 1916. Serial No. 139,128.

To all whom it may concern:

Be it known that I, MELVIN B. BENSON, a citizen of the United States, residing at Superior, in the county of Douglas and State 5 of Wisconsin, have invented certain new and useful Improvements in Telemotors, of which I do hereby declare the following to be a specification.

My invention relates to telemotors, and 10 has for its primary object the provision of improvements in steering gear for vessels. It has for a further object the provision of improved means for actuating the supply or exhaust valve of an engine distant from 15 the station of the operator. With these and other objects in view, it consists of the constructions, combinations and arrangements of parts hereinafter described and claimed.

In the drawings, Figure 1 is a plan view, 20 partly in section and partly in diagram, of my said invention. Fig. 2, is a central vertical longitudinal section of the hereinafter described controller box and pedestal, partly broken away, and of parts positioned thereon, or therein. Fig. 3, is a top plan view 25 partly broken away, of the hereinafter described auxiliary controller case. Fig. 4, is a vertical longitudinal section approximately on the line A—B—C—D— of Fig. 3. Fig. 5, is a vertical transverse section approximately on the line E—F—G—H of said Fig. 3. Fig. 6, is a fragmentary plan view of the hereinafter described reciprocating collector bars, showing the hereinafter 35 described insulation member interposed therebetween. Fig. 7, is a fragmentary plan view partly in diagram showing my invention as applied to the direct operation of a steering gear from which a steam engine is omitted.

40 Heretofore it has been customary to operate the steering gear on large vessels by means of a hand steering wheel having a hub connected with the tiller by cables or chains extending aft from a pilot house near the 45 front of the vessel; or else by oil telemotors in which oil pipes extend aft from cylinder near the rudder head; a piston in the pilot house cylinder being operated by the steering wheel and a piston in the aft cylinder 50 being driven by the piped oil and connected to the valve of a steam steering engine. Where the cable or chain connections are used on an empty vessel of considerable length, they tend to become slack; or when

used on a laden vessel of considerable 55 length they tend to stretch, or to become so taut that they bind. In an oil telemotor, air bubbles tend to accumulate in the pipes and to become compressed therein so that the cylinder pistons do not work in accurate 60 accordance with the steering wheel and the rudder does not take the position indicated by such steering wheel. Further, the oil tends to leak around one end of the piston and so permit the rudder to work toward 65 center when the steering wheel and oil pistons are at one end of their travel.

In the drawings, 1 is a controller case of any suitable structure, preferably mounted on a support of any suitable construction as 70 a pedestal 1^a. Said controller case, when used in connection with a steering gear for vessels, is preferably positioned in a pilot house in the fore part of such vessel. Within said case is positioned an electric contact 75 point 2, preferably of the collector bar type, which is insulated from said case as by an insulation member 3. Said point or bar 2 electrically communicates at all times, by means of any suitable conductor, as by 80 means of a wire 4, with the positive pole of a suitable source of electricity, as a generator 5. Electrically communicating with said point 2 at all times is a movable conductor or contact point 6. It will be observed however that, if desired, said bar 2 may be omitted and said wire 4 may be directly connected to said point 6, without departing from the scope of certain of my claims. Said point 6 is adapted to contact with any 90 one or other of a plurality of contact points 7, positioned within said case and therein insulated from each other and from said case by any suitable insulation means, as by the insulation member 6^a. Each of said 95 points 7 is connected by any suitable conductor as by a wire 7^a, with a corresponding contact point 7^b preferably external to said case, which latter points are spaced from each other by any suitable means, as by an 100 insulation member 8. Adapted to contact at various times with any one or other of said points 7^b is a contact point or bar 9, preferably of the collector bar type. Adapted to contact at other various times with 105 the same such point 7^b is a contact point or bar 10, preferably of the collector bar, type. Adapted to insulate such point 7^b at still

other times from both of said bars 9 and 10, is an insulation member 11 interposed between said points or bars 9 and 10. Said points 9 and 10 and said insulation member 11 are mounted on a carrier of any suitable construction, as upon a reciprocatable plate 12, from which they are preferably insulated in any suitable manner as by an insulation plate 13. Said point or bar 9 is electrically connected with the opposite or negative pole of said source in any suitable manner, as by a contact point 9^a (in normal contact with said bar 9), and by wires 14 and E. It will be understood however that the point 9^a may, if desired, be omitted and that the wire 9^a may be directly connected to the point or bar 9. A relay coil 14^a is interposed at any suitable place in and forms part of a normally open electric current comprising said conductors and points 4, 2, 6, 7, 7^a, 9, 9^a, 14, 14^a, E, and said source. Said point or bar 10, is electrically connected with said opposite or negative pole of said source in any suitable manner as by a contact point 10^a (in normal contact with said bar 10), and by wires 15 and E. It will be understood, however, that, if desired, said point 10^a may be omitted and that said wire 15 may be directly connected to said bar 10. A relay coil 15^a is interposed at any suitable place in and forms part of a normally open circuit comprising said conductors and points 4, 2, 6, 7, 7^a, 7^b, 10, 10^a, 15, 15^a, E, and said source. One brush of the armature of an electric motor 16 is electrically connected with one pole of said source, as to the positive pole thereof, by means of a normally open contact 17. Adapted to be actuated by said coil 14^a to close said contact 17 is an armature 17^a. The other brush of said motor armature is connected with the opposite pole of said source, as to the negative pole thereof, by means of a normally closed contact 18. Adapted to be actuated by said coil 15^a to open said normally closed contact 18 is an armature 18^a, which armature 18^a is adapted in retracted position to close said contact 18. Contrariwise the first said brush of said armature is also connected to the negative pole of said source by means of a normally open contact 19 adapted to be closed by said armature 18^a, when said armature is actuated by said coil 15^a, and the second said brush of said motor armature is also electrically connected with the positive pole of said source by a normally closed contact 20 adapted to be closed by said armature 17^a when the latter armature is in retracted position. A, is a wire connection common to one of the points of each of said contacts 17 and 19. B, is a wire connection common to one of the points of each of said contacts 18 and 20. C, is a wire connection common to the other points of said contacts 17 and 20. D, is a wire

connection common to the other points of said contacts 18 and 19. E, is a wire common to the conductors 14 and 15 and to the conductor B. It will be observed that the wire C connects said contacts 17 and 20 with one brush of said motor armature and that the wire D connects said contacts 18 and 19 with the opposite brush of said motor armature. The wire A connects said contacts 17 and 19 with one pole of said source, and the wire B connects said contacts 18 and 20 with the other pole of said source through the intermediation of a portion of said wire E to which it is preferably connected.

Connected to said wire E is one terminal 80 of the field winding 21 of said motor, the opposite terminal of which field winding is connected to said wire A.

Said plate 12 is adapted to be reciprocated by any suitable mechanism governed 85 or actuated by said motor, as by a worm or screw 22 adapted to engage a nut 23 attached to said plate, said screw having keyed to one of its ends a sprocket wheel 23 engaged by a belt 24 which also engages 90 a sprocket wheel 25 keyed to a shaft 26. A gear 27 is also keyed to said shaft 26 and is engaged by a pinion 28^a keyed to the armature shaft 28 of said motor. When said invention is used for actuating the valve 95 of a steam steering gear, a pinion 29 is also preferably keyed to said shaft 26 and is adapted to engage a gear 30 which is keyed to a worm shaft 31 provided with a worm 32 adapted to engage a nut 33 extending 100 from a slidable plate 34 mounted in guides 35. Pivottally secured at one end to said plate 35 is a connecting rod 36 which is pivotally secured at its opposite end to one end of a walking beam 37 which is pivotally 105 mounted intermediate of its ends on a suitable stationary support, as a girder or bracket 38 and is pivotally secured at its opposite end to one end of a connecting rod 39 which is secured at its opposite end to the 110 valve stem 40^a of the valve 40 of an engine (not shown). If desired said engine and said parts 33 to 40, inclusive, may be omitted and said worm may be adapted to engage a gear 41 keyed to a drum 42. A 115 flexible hauling means 43 is wound upon said drum and is connected at its opposite ends to the corresponding opposite ends of a segment 44 secured to a rudder post 45.

The conductor 6 may be of any suitable 120 construction, preferably in the form of a bar secured intermediate of its ends to a thimble 6^b which is rotatably mounted on a post 6^a, from which thimble said bar 6 is insulated in any suitable manner as by an insulation 125 ring 6^c. Said thimble extends above the cover of said case 1, and there is mounted thereon a manually operatable lever 6^d for turning or swinging the same. The points 7^b, bars 9 and 10 adjacent insulation mem- 130

bers and plate 12 are preferably mounted in an auxiliary controller case G, which may be distant from said case 1.

In operation, assuming the conductor 6 to be in contact with the central one of said contact points 7, and that the insulation member 11 is opposed to the central one of said contact points 7^b, and that the rudder is central, no current will flow and such 10 conditions will be maintained. If then the conductor 6 be swung into contact with any one of said points 7 to the left of said central point 7, thus closing the normally open contact including the point to which conductor 6 is swung, current will flow from the positive pole of said source through the conductors and points 4, 2, 6, 7, 7^a, 7^b, 9, 9^a, 14, 14^a, and E to the negative pole of said source. The coil 14^a is thereby energized 15 and operates the armature 17^a causing it to close the normally open contact 17, and to open said contact 20. The current will now also flow from the positive pole of said source through said field and wire E to the negative pole of said source: also from the positive pole of said source through said contact 19, thence (reversely) through said armature, thence through said contact 20 to the negative pole of said source. The motor being now energized and reversed 20 will, through the transmission mechanism described, move said plate to the right until the transitory contact point 10 has been retracted from the point 7^b in closed circuit and until the insulation member 11 comes into opposition to the point 7^b in circuit, 25 thus opening such circuit and discontinuing the operation. The operation may be renewed by advancing the conductor 6 to another point 7 farther to the right, or may be relatively reversed by moving said conductor 6 to any point 7 to the left of the last prior stop, thus directing the currents through the transitory contact bar 9 instead of through said bar 10.

30 motor now being energized will, through the intermediate mechanism described, cause said plate to move to the left until the transitory contact point or bar 9 is retracted from the contact point 7^b in series with the temporarily closed one of the contacts 7, and until the insulation member 11 comes into opposition to the point 7^b in circuit, thus opening such circuit and discontinuing the operation of the device. The conductor 6 35 may be advanced to another point 7 farther to the left, renewing the operation, or may be shifted to any point to the right of its last prior stop, thus shortening the operation or—if the insulation member has already passed to the left of the point 7^b finally in circuit—reversing the operation by directing the current through the transitory contact 10 instead of through the transitory contact 9. The motor is so geared 40 or connected to the rudder and to said plate 12 that they move together at such speeds and for such distances as will bring the rudder to a stop at the same angle to the right or left of the longitudinal axis of the vessel as the angle of said conductor 6 45 is to such axis. Assuming the conductor 6 to be in contact with the central one of said points 7 and said insulation member 11 to be opposed to the central one of said points 7^b, if the conductor 6 be swung to any point 7 to the right of said central point 7 thus closing the normally open contact including said point 6 and the point 7 to which it is swung, current will flow from 50 the positive pole of said source through the

conductors and points 4, 2, 6, 7, 7^a, 7^b, 10, 10^a, 15, 15^a and E to the negative pole of said source. The coil 15^a, thus energized, operates said armature 18^a causing it to close said normally open contact 19 (and to open 70 said contact 18). The current will now also flow as before from the positive pole of said source through said field and wire E to the negative pole of said source: also from the positive pole of said source through said contact 19, thence (reversely) through said armature, thence through said contact 20 to the negative pole of said source. The motor being now energized and reversed 75 will, through the transmission mechanism described, move said plate to the right until the transitory contact point 10 has been retracted from the point 7^b in closed circuit and until the insulation member 11 comes into opposition to the point 7^b in circuit, 80 thus opening such circuit and discontinuing the operation. The operation may be renewed by advancing the conductor 6 to another point 7 farther to the right, or may be relatively reversed by moving said conductor 6 to any point 7 to the left of the last prior stop, thus directing the currents through the transitory contact bar 9 instead of through said bar 10.

While I have described the preferred form 95 of my invention it is obvious that the construction may be extended, modified or altered in various particulars without departing from the spirit and scope of certain of my claims.

100 What I claim is—

1. The combination of a source of electricity and the armature of an electric motor in circuit therewith, said circuit including a normally open contact and a normally closed contact; a second electric circuit including said source, a normally open contact and a normally closed contact; a third electric circuit including said source a normally open contact and a normally closed contact; a fourth electric circuit including said source, said armature, a normally open contact and a normally closed contact; manually operatable means for closing the normally open contact in either of said second 105 and third circuits; exclusively mechanical means adapted to be operated by said motor for opening the normally closed contact in either of said second and third circuits after the normally open contact of the corresponding said circuit has been closed; means governed by said second circuit for closing the normally open contact of said first circuit and for opening said normally closed contact of said fourth circuit; means governed by said third circuit for closing said normally open contact in said fourth circuit and for opening said normally closed contact in said first circuit; a field member for 110 said motor, one of the terminals of said field 115

member being adapted to electrically communicate with said second and third circuits, the other of said field terminals being adapted to electrically communicate with 5 said first and fourth circuits.

2. The combination of a source of electricity and the armature of an electric motor in circuit therewith, said circuit including a normally open contact; a second electric 10 circuit including said source, a plurality of normally open contacts in parallel, a plurality of normally closed contacts in parallel, each of said normally closed contacts of said second circuit being in series with a corresponding one of said normally open contacts of said second circuit; a third electric 15 circuit including said source, a plurality of normally open contacts in parallel, a plurality of normally closed contacts in parallel, each of said normally closed contacts of said third circuit being in series with a corresponding one of said normally open contacts of said third circuit; a fourth electric 20 circuit including said source, said armature, a normally open contact and a normally closed contact; manually operatable means for closing and reopening any one or other of the normally open contacts of said second and third circuits; means 25 adapted to be actuated exclusively by said motor for opening any one of said normally closed contacts of said second and third circuits at an interval after said normally open contact in series therewith has been closed, 30 said means being adapted to reclose such normally closed contact after said normally open contact in series therewith has been reopened and after another of said normally opened contacts has been closed; means governed 35 by said second circuit for closing the normally open contact of said first circuit and for opening the normally closed contact of said fourth circuit; means governed by said third circuit for closing said 40 normally open contact of said fourth circuit and for opening said normally closed contact of said first circuit; a field member for said motor, one pole of said field member being connected to one of the conductors in 45 said second and third circuits, the other pole of said field being connected to one of the conductors in said first and fourth circuits.

3. The combination with a source of electricity and the armature of a motor in 50 circuit therewith, said circuit including a normally open contact; a second electric circuit including a source of electricity, a normally open contact, a normally closed contact and only one relay coil; manu-

ally operable means for closing the normally open contact of said second circuit, exclusively mechanical means adapted to be operated by said motor for opening the normally closed contact of said second circuit, means governed by said coil for closing the normally open contact of said first circuit. 60 65

4. The combination with a source of electricity of the armature of a motor in circuit therewith, said circuit having a normally open contact and a normally closed contact; a second electric circuit including said source, a normally open contact, a normally closed contact and a relay coil; means adapted to be manually operated to close the normally open contact of said second circuit; means adapted to be operated by said motor to open the normally closed contact of said second circuit at an interval after the closing of the normally open contact of said second circuit; means adapted to be operated by said coil to close the normally open contact of said first circuit, the armature leads of said motor being adapted to be short circuited through said normally closed contact of said first circuit when said second circuit is open, the field of said motor being in constant circuit with said source. 70 75 80

5. The combination with an electric motor the armature brushes of which are adapted to be normally short circuited through two normally closed contacts; of a second electric circuit including a source of electricity, a normally open contact, one of the normally closed contacts of said short circuit, and the armature of said motor; a third electric circuit including said source a normally open contact, a normally closed contact and only one relay coil; means adapted to be manually operated to close the normally open contact of said third circuit; means adapted to be operated by said motor for opening the normally closed contact of said third circuit; means governed by said coil for opening only one of the normally closed contacts of said short circuit and for closing the normally open contact of said second circuit, the field of said motor being in constant circuit with said source. 90 95 100 105 110

In testimony whereof I hereunto affix my signature in presence of two witnesses.
